UNITED STATES PATENT OFFICE.

DANIEL E. HENNESSY, OF HOLYOKE, MASSACHUSETTS, ASSIGNOR TO HERBERT W. COWAN, J. LEWIS WYCKOFF, AND EDWARD N. WHITE, AS TRUSTEES, DOING BUSINESS AS THE COWAN TRUCK COMPANY.

ELEVATING-TRUCK.

1,373,069.

Specification of Letters Patent. Patented Mar. 29, 1921.

Application filed July 2, 1915. Serial No. 37,654.

To all whom it may concern:

Be it known that I, DANIEL E. HENNESSY, a citizen of the United States, residing at Holyoke, county of Hampden, and State of Massachusetts, have invented certain new and useful Improvements in Elevating-Trucks, of which the following is a clear, full, and exact description.

This invention relates to an improvement in elevating trucks of the type in which an upper platform is elevated with respect to the base in order to pick up, carry about, and deliver loads from place to place.

The object of the invention is to improve the construction of such trucks so as to facilitate the elevating of the platform by means of the steering handle acting as a lever and to render said steering handle free for up-and-down and lateral movement when desired for steering and hauling the truck from one place to another.

A further object is to provide secure locking means for holding the platform in raised position under all conditions of use and which may be readily unlocked when desired, to permit the platform to lower.

Further objects and advantages of the invention will be apparent from the following description and accompanying drawings which disclose the preferred embodiment of my invention.

In the drawings, Figure 1 is a side elevation of the truck;

Fig. 2 is a plan of the same;

Fig. 3 is an enlarged detail of the connection between the handle and the platform when the platform is raised, the dotted lines showing the parts in lifting engagement, and the solid lines showing the position of the same parts when disengaged;

Fig. 4 is a plan of the parts shown in solid lines of Fig. 3;

Fig. 5 is a similar view showing the platform lowered, the solid lines showing the parts disengaged and the dotted lines the position of the parts, preparatory to engagement; and

Fig. 6 is a view similar to Fig. 5 showing the parts at a later stage after the same have been engaged.

Figs. 7 and 8 are detailed views of a modified form of engaging member with a part in section to show more clearly the slotted portion thereof;

Fig. 9 is an enlarged detail of the inside face of the end of one engaging arm.

Referring more particularly to the drawings, the truck is of the usual type comprising the lower base frame 1 supported on rear wheels 4 and front steering wheel 3 which has the usual head 35 swiveled in the frame for being manipulated to steer the truck. Upon the upper portion of the swiveled head 35 is pivotally mounted at 22 the steering handle 21, so that when free and disengaged as hereinafter described, it may be moved both up and down and laterally in guiding and hauling the truck.

The upper platform indicated at 2, is connected to the lower frame 1, preferably by means of swinging links 5 at the rear, and 6 at the front, so that said platform may have an up-and-down movement with respect to said base frame. The links 5 are pivotally connected at 10 to the platform and at 11 to the base, and the links 6 are pivotally connected at 12 to the platform and at 13 to the base. A checking device 7 is pivotally connected at 14 to the cross member 8 at the rear of said base frame, and at 15 to the cross member 9 at the forward part of said platform to check the too rapid descent of said platform when it is released and allowed to lower. This checking device may be of any usual construction common with door checks, and it is not deemed necessary to describe it further in detail, suffice to say that it permits the raising of the platform without appreciable resistance but controls the descent of the platform so that it will be comparatively slow and easy.

In the present invention, the steering handle is utilized as the operating lever for elevating the platform, and the means for connecting said handle to the platform are preferably as follows: Upon the cross-shaft 12 at the forward part of the platform 2, is pivotally mounted an engaging member 16 preferably constructed with two spaced side arms 17 and 17^a. The engaging member 16 is provided with angular slots, one slot on the inner face of each side arm 17 and 17^a formed by recessing out said side arms, such as 19 for arm 17, and 19^a for arm 17^a, all as shown more clearly in Figs. 5 and 6. The opposite ends of these slots are open so that the ends of a cross-pin 20

carried on a projection of the handle 21 may pass in and out of said slots at either end. Each slot is formed with an angular path therethrough, as shown, so as to retain the 5 ends of cross-pin 20 therein in certain positions of the handle and engaging member, the angular shape of the slot providing a surface which bears against the upper side of the pin 20 and thus supports the arm 17 10 against the tendency of gravity to restore it to its lowermost position, and a second surface which engages a lateral side of the pin 20 and forms the positive connection between the platform and the handle. 15 Similar surfaces are provided in the modified construction hereinafter described. It will be understood, of course, that the invention is not restricted to the particular connections between the platform and the 20 handle which are herein shown and described.

Upon a bracket 30 fixed to the forward part of the base frame 1, is pivotally mounted at 24 a foot-lever 23. The foot-lever may be weighted so as to normally stay in the positions shown in Figs. 1, 3 and 6, but I preferably provide a spring 29 to normally hold it in this position. This 25 foot-lever has two depending arms, one short arm 25 at the left and one long arm 27 at the right. The longer arm 27 is adapted to abut against a boss 28 formed on the engaging member 16 for lifting said member to place it in engaging position relative to the handle, and the short arm 25 is adapted to abut against the front part 30 of the platform 2 when the latter is elevated, as shown in Fig. 1, to throw said platform rearwardly to bring said links 5 and 6 to the rear of their vertical position for lowering the platform. The platform 2 is adapted to be elevated to bring the links 5 and 6 forward of their vertical positions so that said links 6 will rest against 35 a stop 37 on the base frame and thus tend to hold the upper platform locked in its elevated position, as shown in Figs. 1 and 3. Under some circumstances, such as when traveling up a steep incline, it is desirable 40 to provide further means for locking the platform in its raised position, and for this purpose the left arm 17 of the engaging member has a laterally extending boss 18 which is adapted, when said engaging member 45 is released, to drop into the position shown in Figs. 3 and 4, and stand in front of a similar laterally extending boss 26 fixed to the foot-lever 23 and thus form 50 interlocking means to prevent the platform from being accidentally lowered.

Operation: The operation of the truck is as follows. Assume that the parts are in the position shown in solid lines in Fig. 5 with the upper platform down and the handle 55 21 freely movable back and forth or

laterally for steering the truck. When it is desired to elevate the platform, the foot treadle 23 is first operated to raise the engaging member 16 into the position shown in dotted lines in Fig. 5 so that the lower 70 end of the slots 19, 19^a, will be above the arc described by the cross-pin 20. The handle 21 is then manipulated to bring the cross-pin 20 to the position shown in dotted lines in Fig. 5 and the foot-lever is released 75 to allow the engaging member to drop, bringing the slotted arms 17, 17^a, into engagement with the cross-pin 20, as shown in Fig. 6. The handle 21 may then be swung forwardly and downwardly to elevate the 80 platform to the position shown in Fig. 1. If, then, it is desired to draw the truck and have the handle 21 free for steering the same, it is only necessary to swing the handle backwardly to the position shown in 85 solid lines in Fig. 3, whereby the pin 20 will pass out the upper open ends of the slots 19, 19^a, and release the engaging member 16 so that it will drop into the position shown in solid lines in Fig. 3. When 90 the engaging member drops into this position, it will be noted that its boss 18 stands in front of the boss 26 on the foot-lever 23, as shown in Fig. 4, and thus any backward movement of the platform necessary for descent is prevented. The truck may then 95 be drawn by means of the handle 21 which is freely movable in all directions. When it is desired to release the load, the foot-lever 23 is again operated to depress the 100 boss 26 below the boss 18 and thus permit the platform to swing rearwardly when, by the further movement of the foot-lever 23, the arm 25 is brought to bear against the platform 2 for throwing it rearwardly. 105 The platform will then fall into the position shown in Fig. 5, its descent being controlled by the checking device 7.

In Figs. 7, 8 and 9, I have shown a modified form of engaging member for being connected with the handle 21. This engaging member comprises pivoted side arms 117 similar to engaging member 17 heretofore described, and at the outer ends of these side arms are provided slots 119 in the inner 115 face of said arms, which slots are open only at their upper ends as at 120, see Fig. 9. These slots, furthermore, are formed with an offset portion 121 at their lower end so as to retain the pin 20 therein. In Fig. 7 120 the parts are illustrated with the upper platform down, and as therein shown, the engaging member 117 may be moved upwardly by the operation of the foot-lever 23 to bring the pin 20 within the upper end of 125 slot 120. In dotted lines I have shown the handle and engaging member just previous to the entrance of the pin 20 in slot 120, and in solid lines the position of the parts when the handle has been swung slightly forward 130

to retain the pin 20 within the slot. The platform may then be lifted by the operation of the handle as described in connection with the previous figures. In Fig. 8 is shown the position of the parts with the platform elevated, and in solid lines the handle and engaging member in connection with one another. By moving the handle upwardly from this position to the position shown in dotted lines, it will be obvious that the parts will be disengaged, allowing the engaging member to drop down and permitting thereafter free movement of the handle 21 both up and down and laterally. It will be noted from an examination of the drawings that in both forms of connections herein shown and described, the construction and arrangement of the slot is such that the backward movement of the pin 20 not only carries the pin out of the slot, but a continuation of this movement, in the event that the link or engaging member 17 fails to fall under the action of gravity, will insure the movement of the engaging member 17 out of the path of movement of the handle.

While I have shown and described two embodiments of my invention, it is obvious that various changes in details may be made and equivalent constructions adopted for the same purpose, without departing from the spirit of my invention as set forth in the following claims.

What I claim as new is:-

35 1. In an elevating truck, in combination, a base, a platform mounted on said base for up and down movement thereon, a pivoted handle and means for connecting said platform to said handle to effect the raising of
40 said platform by the movement of said handle comprising a member movable into the path of movement of said handle and automatically movable out of said path when disengaged from said handle, said member
45 and said handle having coöperating engaging portions by which a positive connection between the platform and said member may be obtained for one direction of the movement of said handle about its pivot, and said
50 engaging portions being so arranged that a different movement of said handle about its pivot effects the complete disengagement of said parts and the movement of said member toward its position out of the path of movement of said handle.
55

2. In an elevating truck, in combination, a base, a platform mounted on said base for up and down movement thereon, a pivoted handle and means for raising said platform by the movement of said handle comprising a member movable into and out of the path of movement of said handle, said member and said handle having coöperating engaging portions by which a positive connection between the member and said handle may be

obtained for one direction of the movement of said handle about its pivot, and said engaging portions presenting surfaces so shaped and so arranged that a different movement of said handle about its pivot effects by virtue of the movement of said surfaces into a different relation to each other the complete disengagement of said parts and the movement of said member out of said path. 75

3. In an elevating truck, in combination, a base, a platform mounted on said base for up and down movement thereon, a pivoted handle, means for effecting the elevation of said platform through the movement of said handle comprising a member arranged to be connected to and disconnected from said handle, said connections presenting coöperating surfaces so located that the movement of said handle in one direction insures, through the relative movement of said surfaces, the movement of said member out of the path of movement of said handle. 85

4. In an elevating truck, in combination, a base, a platform mounted on said base for up and down movement thereon, a pivoted handle, means for effecting the movement of said platform through the movement of said handle comprising a member tending to remain in, or to return to, a position out of the path of movement of said handle and arranged to be connected to and disconnected from said handle, the connections between said member and said handle presenting coöperating surfaces so shaped and so arranged with respect to the path of movement of said handle that movement of said handle in one direction effects a relative movement of disconnection of said parts and a positive movement of said member toward its position to move out of the path of movement of said handle. 90 95 100 105

5. In an elevating truck, in combination, an elevating platform, supporting and steering wheels therefor, a pivoted steering and draft handle, and means for connecting said platform to said handle to effect the raising of said platform by the movement of said handle, comprising a member tending to gravitate into a position where it will not interfere with the movements of said handle, said connections comprising a support by which said member is sustained against its tendency to gravitate out of connecting relation to said handle but which is arranged to be moved upon a movement of said handle in one direction out of sustaining relation to said member.

6. In an elevating truck, in combination, an elevating platform, supporting and steering wheels therefor, a pivoted steering and draft handle and means for connecting said platform to said handle to effect the raising of said platform by the movement of said handle, comprising parts having inter- 130

locking connection and having their interlocking surfaces so shaped and so arranged that they are brought into unlocking relation by relative movement of said parts as said handle moves in one direction, the said interlocking parts being so mounted and their unlocked relation being such that one of said parts is permitted to gravitate out of the path of relative movement of said parts when said connection is broken.

7. In an elevating truck, in combination, an elevating platform, supporting and steering wheels therefor, a pivoted steering and draft handle, means for effecting the raising of said platform by the movement of said handle comprising a member movable into and out of the path of movement of said handle, and means for supporting said member out of the path of movement of said handle movably supported in position to be operated to lift said member into operative relation to said handle.

8. In an elevating truck, in combination, an elevating platform, supporting and steering wheels therefor, a pivoted steering and draft handle, and means for effecting the raising of said platform by the movement of said handle, comprising a member connected to said platform and arranged to be connected to, and disconnected from, said handle, and movable into and out of the path of movement of said handle, the connections between said member and said handle comprising coöperating engaging portions arranged to be brought into coöperative relation by the movement of said handle in one direction and having one of said engaging portions so supported by the other that said connection is interrupted by the movement of said handle in another direction, and means for moving said member into the path of movement of said handle.

9. In an elevating truck, in combination, an elevating platform, supporting and steering wheels therefor, a combined draft and steering handle arranged to swing about both vertical and horizontal axes, means for connecting said platform to said handle to utilize the vertical swinging movement thereof to elevate said platform, said means comprising a member movable into and out of the path of the movement of said handle about its vertical axis arranged to be connected to and disconnected from said handle, and means for supporting said member out of the path of the horizontal movement of said handle, movably mounted in position to be operated to bring said member into connecting relation to said handle.

10. In an elevating truck, in combination, an elevating platform, supporting and steering wheels therefor, a pivoted steering and draft handle, means for connecting said platform to said handle to effect the elevating movement of said platform through the

movement of said handle, comprising a member arranged to gravitate into inoperative relation to said handle when said handle moves in one direction, said member and said handle having coöperating supporting portions whereby said member may be held in operative relation to said handle upon the movement of said handle in the other direction, and manually controlled means for lifting said member into the path of movement of said handle to permit said operative connection.

11. In an elevating truck, in combination, an elevating platform, supporting and steering wheels therefor, a pivoted steering and draft handle, means for connecting said platform to said handle to effect the elevating movement of said platform through the movement of said handle comprising a member arranged to gravitate into inoperative relation to said handle when said handle moves in one direction, said member and said handle having coöperating supporting portions whereby said member may be held in operative relation to said handle upon the movement of said handle in the other direction, and manually controlled means for lifting said member into the path of movement of said handle to effect said operative connection, said means being constructed and arranged to be operated to effect the lowering of said platform when said platform is in elevated position.

12. In an elevating truck, in combination, an elevating platform, supporting and steering wheels therefor, a pivoted steering and draft handle, means for connecting said platform to said handle to effect the raising of said platform by the movement of said handle, comprising a member constantly connected to said platform and arranged to be connected to and disconnected from said handle, and means coöperating with said member when in disconnected relation for locking said platform in elevated position, said member and said locking means being normally unconnected.

13. In an elevating truck, in combination, an elevating platform, supporting and steering wheels therefor, a pivoted steering and draft handle, means for effecting the elevation of said platform by the movement of said handle comprising a member arranged to be connected to and disconnected from said handle and movable into and out of the path of movement of said handle, and means coöperating with said member when out of the path of movement of said handle for locking said platform in elevated position, said means being normally unconnected with said member.

14. In an elevating truck, in combination, an elevating platform, supporting and steering wheels therefor, a pivoted steering and draft handle, means for effecting the raising

- of said platform by the movement of said handle comprising a link connected to said platform and arranged to be connected to and disconnected from said handle, and 5 means upon said base, coöperating with said link when said platform is in elevated position and said link is disconnected from said handle, to lock said platform against movement to lowered position, said means being 10 normally unconnected with said link.
15. In an elevating truck, in combination, an elevating platform, supporting and steering wheels therefor, a pivoted steering and draft handle, means for effecting the raising 15 of said platform by the movement of said handle, comprising a member movable into and out of the path of movement of said handle, and means for supporting said member out of the path of movement of said 20 handle, said means having a part constructed to coöperate with said member, when said platform is elevated, to lock said platform in elevated position, said supporting means and said member being normally 25 unconnected.
16. In an elevating truck, in combination, a base, a platform mounted on said base for up and down movement thereon, means for carrying said platform between its ele- 30 vated and lowered positions arranged to be brought into a position in which said platform tends to remain in elevated position; means for locking said platform in ele- 35 vated position, and independent manually-controlled means comprising a lever constructed and arranged to effect by a single continuous movement the release of said locking means and then the positive move- 40 ment of said platform out of its elevated position.
17. In an elevating truck, in combination, an elevating platform, supporting and steering wheels therefor, a pivoted steering and draft handle, means for effecting the raising 45 of said platform by the movement of said handle, comprising a member movable into and out of the path of movement of said handle, means coöperating with said member to lock said platform in elevated position, and means for bringing said member into operative relation to said handle, when 50 said platform is in lowered position, said means being so located that it may be operated to effect the unlocking of said platform when said platform is in elevated position.
18. In an elevating truck, in combination, an elevating platform, supporting and steering wheels therefor, a pivoted steering and draft handle, means for effecting the elevation 60 of said platform by the movement of said handle, comprising a connecting member arranged to be moved into and out of a position in which it connects said handle and 65 said platform, means for locking said plat- form in elevated position, and means for effecting the unlocking of said platform constructed and arranged to engage and move said platform toward lowered position by a continuation of the unlocking move- 70 ment of said means.
19. In an elevating truck, in combination, an elevating platform, supporting and steering wheels therefor, a pivoted steering and draft handle, means for connecting said plat- 75 form to said handle to effect the raising of said platform by the movement of said handle, comprising an engaging member movable into and out of the path of movement of said handle, means for maintaining said member in engagement with said handle when said handle moves in one direction, constructed to permit a relative movement of said member and said handle into disengagement when said handle is moved in the 80 opposite direction, and means rendered operative only by the disengagement of said engaging member from said handle, when the platform is up, to effect the locking of said 85 platform against descent. 90
20. In an elevating truck, in combination, a base, a platform mounted on said base for up and down movement thereon, a pivoted handle, means for connecting said platform to said handle to effect the raising of said 95 platform by the movement of said handle, comprising an engaging member movable into and out of the path of movement of said handle, means for maintaining said member in engagement with said handle when said handle moves in one direction, constructed to permit a relative movement of said member and said handle into disengagement when said handle is moved in the opposite 100 direction, and means rendered operative by the disengagement of said engaging member from said handle, when the platform is up, to effect the locking of said platform against descent. 105
21. In an elevating truck, in combination, a base, a platform mounted on said base for up-and-down movement thereon, a pivoted 110 handle having a back and forth movement, means for connecting said platform to said handle for being raised thereby when said handle is moved forwardly, comprising an engaging member connected to said plat- 115 form and having a pin-and-slot connection with said handle, said slot having an opening to the exterior of the part in which it is formed and being so arranged with respect to the path of relative movement of 120 said handle and said member that the pin will be disengaged therefrom and free the handle from said engaging member, upon the mere backward movement of said handle after the platform is raised. 125

22. In an elevating truck, in combination, an elevating platform, supporting and steering wheels therefor, a pivoted steering and draft handle, means for connecting said platform to said handle to effect the raising of said platform by the movement of said handle, comprising an engaging member movable into and out of the path of movement of said handle, means for maintaining said member in engagement with said handle when said handle moves in one direction, constructed to permit a relative movement of said member and said handle into disengagement when said handle is moved in the opposite direction, and a foot-lever operable on said engaging member when said platform is down to place said engaging member in engaging position with respect to said handle.

23. In an elevating truck, in combination, a base, a platform mounted on said base for up-and-down movement thereon, a pivoted handle having a back and forth movement, means for connecting said platform to said handle for being raised thereby when said handle is moved forwardly, comprising an engaging member mounted on said platform and arranged to be detachably connected with said handle, and means rendered operative by the disengagement of said engaging member from said handle, when the platform is up, to effect the locking of said platform against descent.

24. In an elevating truck, in combination, a base, a platform mounted on said base for up-and-down movement thereon, a pivoted handle having a back and forth movement, means for connecting said platform to said handle for being raised thereby when said handle is moved forwardly, comprising an engaging member mounted on said platform and arranged to be detachably connected with said handle, and means rendered operative by the disengagement of said engaging member from said handle, when the platform is up, to effect the locking of said platform against descent, comprising a part on said engaging member and a part carried on said base to interlock with the part on said engaging member.

25. In an elevating truck, in combination, a base, a platform mounted on said base for up-and-down movement thereon, a pivoted handle having a back and forth movement, means for connecting said platform to said handle for being raised thereby when said handle is moved forwardly, comprising an engaging member mounted on said platform and arranged to be detachably connected with said handle, and means rendered operative by the disengagement of said engaging member from said handle, when the platform is up, to effect the locking of said platform against descent, comprising a part on said engaging member and a part movably car-

ried on said base to interlock with the part on said engaging member, said movable part being movable to unlock said locking means.

26. In an elevating truck, in combination, a base, a platform mounted on said base for up and down movement thereon and so connected to, and arranged with respect to, said base that it may be moved upwardly into a self-locking position, a pivoted handle, means for connecting said platform to said handle to effect the raising of said platform by the movement of said handle, comprising an engaging member movable into and out of the path of movement of said handle, means for maintaining said member in engagement with said handle when said handle moves in one direction, constructed to permit relative movement of said member and said handle into disengagement when said handle moves in the opposite direction, and a foot-lever arranged when operated to engage and move said platform from its upper locked position.

27. In an elevating truck, in combination, a base, a platform mounted on said base for up and down movement thereon and so connected to, and arranged with respect to, said base that it may be moved upwardly into a self-locking position, a pivoted handle, means for connecting said platform to said handle to effect the raising of said platform by the movement of said handle, comprising an engaging member movable into and out of the path of movement of said handle, means for maintaining said member in engagement with said handle when said handle moves in one direction, constructed to permit relative movement of said member and said handle into disengagement when said handle moves in the opposite direction, and a foot-lever having a part arranged to interlock with a part on said engaging member when the latter is disengaged from the handle, with the platform in raised position, said foot-lever being so mounted that it may be operated both to disengage said interlocking parts and to move said platform from its upper self-locking position.

28. In an elevating truck, in combination, a base, a platform mounted on said base for up and down movement thereon and so connected to, and arranged with respect to, said base that it may be moved upwardly into a self-locking position, a pivoted handle, means for connecting said platform to said handle to effect the raising of said platform by the movement of said handle, comprising an engaging member movable into and out of the path of movement of said handle, means for maintaining said member in engagement with said handle when said handle moves in one direction, constructed to permit relative movement of said member and said handle into disengagement when said handle moves in the opposite direction, and a foot-lever having one arm constructed and arranged to

act on said engaging member and put it in engaging position with respect to said handle when the platform is down and another arm constructed and arranged to act upon 5 said platform, when it is up, to move said platform from its upper self-locking position.

29. In an elevating truck, in combination, 10 a base, a platform mounted on said base for up-and-down movement thereon, a pivoted handle having a back and forth movement, means for connecting said platform to said handle for being raised thereby when said handle is moved forwardly, comprising an 15 engaging member having a pin-and-slot connection with said handle, said slot being open at each end and formed with an angular path therethrough, so that the pin will be retained within said slot when said handle is in certain positions and will be free 20 to pass out of said slot when said handle is in other positions.

30. In an elevating truck, in combination, 25 a base, a platform mounted on said base for up-and-down movement thereon, a pivoted handle having a back and forth movement, means for connecting said platform to said handle for being raised thereby when said handle is moved forwardly, comprising an 30 engaging member having a pin-and-slot connection with said handle, said slot being open at each end and formed with an angular path therethrough, so that said pin may 35 pass out of one end of said slot when the platform is up and pass into the other end of said slot when the platform is down.

31. In an elevating truck, the combination 40 with an elevating platform, supporting and steering wheels therefor, a pivoted steering handle and means for connecting said platform to said handle to elevate said platform, comprising a member movable into 45 and out of the path of movement of said handle, of a foot lever for effecting the movement of said connecting member into the path of movement of said handle, and means for locking said platform against descent when said connecting member is disconnected from the handle, said foot lever 50 being arranged to trip said locking means when said platform is in elevated position and to effect the aforesaid movement of said connecting member when the platform is in lowered position.

32. In an elevating truck, the combination 55 with an elevating platform, supporting and steering wheels therefor, and a pivoted steering handle, of means for connecting said platform to said handle to elevate said platform, comprising a link normally connected to said platform and arranged to 60 gravitate out of the path of movement of said handle when disconnected therefrom, and a foot lever for raising said link into position to be connected to said handle.

33. In an elevating truck, the combination 65 with an elevating platform, supporting and steering wheels therefor, and a pivoted steering handle, of means for connecting said platform to said handle to elevate said platform, comprising a link normally connected to said platform and arranged to 70 gravitate out of the path of movement of said handle when disconnected therefrom, a foot lever for raising said link into position to be connected to said handle, and means for locking said platform in elevated 75 position, said foot lever being arranged to lift said link into connecting position when the platform is down and to trip said locking means when the platform is up.

34. In an elevating truck, the combination 80 with a base, an elevating platform, a front steering wheel having a swivel connection with said base, a steering handle pivoted to rock upon the free upper part of said swivel, of means for connecting said platform to said handle to elevate said platform, comprising a link arranged to gravitate out 85 of the path of movement of said handle when disconnected therefrom, a foot-lever for raising said link into position to be connected to said handle, and means for locking the platform in elevated position, said foot lever being arranged to lift said link into 90 connecting position when the platform is down and to trip said locking means when the platform is up, and said truck base having at its forward end an elevated portion 95 beneath which the steering wheel turns, above which said steering handle swings, and upon which said foot lever is pivoted, a member of said locking means is located and said link rests when out of the path of movement of said handle.

35. In an elevating truck, the combination 100 with a base, an elevating platform and a pivoted steering handle, of means for connecting said platform to said handle to elevate said platform, comprising a member normally out of connecting position when the handle is used for steering, and a treadle for moving said member into position for effecting said connection.

36. In an elevating truck, the combination 105 with a base, an elevating platform and a pivoted steering handle, of means for connecting said platform to said handle to elevate said platform, comprising a link normally connected to one of said parts and 110 tending to move out of connected relation to the other, and a treadle for moving said link into position for effecting said connection.

37. In an elevating truck, in combination, 115 a base, a platform mounted on said base for up and down movement thereon, a pivoted handle and means for raising said platform by the movement of said handle comprising 120 a member movable into the path of move- 125

ment of said handle and automatically movable out of said path when disengaged from said handle, said member and said handle having coöperating engaging portions by which a positive connection between the member and said handle may be obtained for one direction of the movement of said handle about its pivot, and said engaging portions being so arranged that a different movement of said handle about its pivot effects the complete disengagement of said parts and the movement of said member toward its position out of the path of movement of said handle.

15 38. In an elevating truck, the combination with an elevating frame, supporting and steering wheels therefor and a pivoted steering and draft handle, of means for connecting said frame to said handle to elevate 20 said frame, comprising a member normally out of connecting position when the handle is used for steering, and means for moving said member into position to effect said connection.

25 39. In an elevating truck, the combination with an elevating frame, supporting and steering wheels therefor and a pivoted steering and draft handle, of means for connecting said frame to said handle to elevate 30 said frame, comprising a member normally out of connecting position when the handle is used for steering, and means for moving said member into position to effect 35 said connection, said means extending into position for convenient manipulation by the operator of the steering and draft handle.

40 40. In an elevating truck, the combination with an elevating frame, supporting and steering wheels therefor and a steering 45 and draft handle, of means for connecting said frame to said handle to elevate said frame, comprising a link normally connected to one of said parts and tending to move out of connecting relation to the other, and means for moving said link into position to effect said connection.

45 41. In an elevating truck, the combination with an elevating frame, supporting and steering wheels therefor and a pivoted steering handle, of means for connecting said frame to said handle to elevate said frame, comprising a link connected to said frame and movable thereon out of the path of the normal steering movement of said handle, and a treadle for moving said link into connecting relation to said handle.

50 42. In an elevating truck, the combination with an elevating frame, supporting and steering wheels therefor and a pivoted steering and draft handle, of means for connecting said frame to said handle to elevate said frame comprising a link connected to said frame and tending normally to gravitate out of the path of the normal steering movement of said handle, and means for moving

said link into connecting relation to said handle.

43. In an elevating truck, the combination with a base, an elevating platform movable forwardly and upwardly on said base 70 into elevating position, and a pivoted steering and draft handle, of means for connecting said platform to said handle to effect the forward and upward movement of said platform by the movement of said handle, 75 comprising a link carried by said platform and tending to move out of the way of said handle when disconnected therefrom, and means for moving said link into connecting relation to said handle having a foot operating member extending into proximity to the forward end of said truck.

44. In an elevating truck, the combination with an elevating frame, supporting and steering wheels therefor and a pivoted 85 steering and draft handle, of means for connecting said frame to said handle to elevate said frame, comprising a link connected to said frame and shaped to embrace said handle and to be connected thereto on 90 opposite sides thereof, said link tending when disconnected from said handle to move out of the path of the normal steering movement of said handle, and means for moving said link into connecting relation to said 95 handle.

45. In an elevating truck, the combination with an elevating frame, supporting and steering wheels therefor and a pivoted steering and draft handle, of means for connecting said frame to said handle to elevate 100 said frame, comprising a link pivotally mounted upon said frame to swing under the action of gravity out of the path of the normal steering movement of said handle, 105 said link being shaped to embrace said handle and to be connected thereto on opposite sides thereof to hold said handle to a definite path of frame-elevating movement, and means arranged to be manipulated by the 110 operator in erect position at the handle for moving said link into connecting position.

46. In an elevating truck, the combination with an elevating frame, supporting and steering wheels therefor and a pivoted 115 steering and draft handle, of means for temporarily connecting said handle to said frame to elevate said frame, comprising a yoke-like link extending forward from said frame and adapted to embrace said handle 120 and to be connected to said handle on opposite sides thereof, said link being arranged to drop out of the path of the normal steering movement of said handle when disconnected therefrom.

47. In an elevating truck, the combination with an elevating frame, supporting and steering wheels therefor and a pivoted steering handle, of means for connecting said frame to said handle to elevate said frame, 125

- comprising a link pivotally connected to said frame, extending forward therefrom and arranged to drop out of the path of the normal steering movement of said handle 5 when disconnected from said handle, said link being shaped to embrace said handle and said handle having members extending from opposite sides thereof for engagement with the embracing parts of said link, one of 10 said pairs of engaging parts being hook-shaped and opening in a direction to permit said link to drop upon a backward movement of said handle at the end of the elevating movement.
- 15 48. In an elevating truck, the combination with an elevating frame, supporting and steering wheels therefor and a pivoted steering and draft handle, of means for temporarily connecting said frame to said 20 handle to elevate said frame, comprising a yoke like link pivoted upon said frame and adapted to embrace said handle and to be connected to said handle on opposite sides thereof, said handle comprising an arm ar- 25 ranged at an angle thereto and provided with members for connection to the arms of said yoke.
49. In an elevating truck, the combination with an elevating frame, supporting 30 and steering wheels therefor and a pivoted steering and draft handle, of means for connecting said frame to said handle to elevate said frame, comprising a link connected to said frame and shaped to embrace said handle and to be connected thereto on opposite sides thereof, said link tending when disconnected from said handle to move out of the path of the normal steering movement of said handle, and means for moving said link 35 into connecting relation to said handle.
50. In an elevating truck, the combination with a base, an elevating platform, and a steering and draft handle, of means on said 40 base for elevating said platform upon a movement of said platform lengthwise of said base and for retaining said platform in an elevated position from which it may be pushed to permit it to gravitate to low- 45 ered position, means for connecting said platform to said handle to effect said lengthwise movement, adapted to be disconnected when said platform is in the aforementioned elevated position, and means extending into 50 position for convenient manipulation by the operator of the steering and draft handle for pushing said platform out of said aforementioned elevated position.
51. In an elevating truck, the combination with an elevating frame, supporting 55 and steering wheels therefor and a pivoted steering and draft handle, of means for connecting said frame to said handle to elevate said frame adapted to be disconnected at the end of the elevating movement, a lock for locking said frame in elevated position, and 60 foot operated means for releasing said lock comprising means for accelerating the downward movement of said frame.
52. In an elevating truck, the combination with an elevating frame, supporting and steering wheels therefor and a pivoted steering and draft handle, of means for connecting said frame to said handle to elevate said frame adapted to be disconnected at the end of the elevating movement, a lock for locking 65 said frame in elevated position, and foot operated means for releasing said lock comprising means for accelerating the downward movement of said frame, said foot operated means also comprising means operable when said frame is in lowered position to bring said connecting means into position for effecting the connection between said handle and said frame. 70
53. In an elevating truck, the combination with an elevating frame, supporting and steering wheels therefor and a pivoted steering handle, of means for connecting said frame to said handle to elevate said frame, comprising a member normally out of connecting position when the handle is used for steering, a lock for holding said frame in elevated position, and means for moving 75 said member into position to effect said elevating connection, said last mentioned means being operable in the elevated position of said frame to release said lock. 80
54. In an elevating truck, the combination with a base, an elevating platform, and a steering and draft handle, of means on said 85 base for elevating said platform upon a movement of said platform lengthwise of said base and for retaining said platform in an elevated position from which it may be pushed to permit it to gravitate to low- 90 ered position, means for connecting said platform to said handle to effect said lengthwise movement, adapted to be disconnected when said platform is in the aforementioned elevated position, and means extending into 95 position for convenient manipulation by the operator of the steering and draft handle for pushing said platform out of said aforementioned elevated position. 100
55. In an elevating truck, the combination of an elevating frame, supporting and steering wheels therefor and a pivoted steering and draft handle, of means for connecting said frame to said handle to elevate said frame adapted to be disconnected at the end of the elevating movement, a lock for locking 105 said frame in elevated position, a fluid check for retarding the return movement of said frame, and means for effecting an initial movement of said frame in the return 110 direction when said lock is released. 115
56. In an elevating truck, the combination of an elevating frame, supporting and steering wheels therefor and a pivoted steering and draft handle, of means for con- 120

necting said frame to said handle to elevate said frame adapted to be disconnected at the end of the elevating movement, a lock for locking said frame in elevated position, a fluid check for retarding the return movement of said frame and means extending into position for convenient manipulation by the operator of the steering and draft

handle for imparting to said frame an initial impetus in the return direction.
